UNITED STATES PATENT OFFICE.

AUGUST ALLEN, OF LEAD, SOUTH DAKOTA.

SAW-FRAME.

No. 839,696.

Specification of Letters Patent.

Patented Dec. 25, 1906.

Application filed July 7, 1906. Serial No. 326,148.

To all whom it may concern:

Be it known that I, AUGUST ALLEN, a citizen of the United States, and a resident of Lead, in the county of Lawrence and State 5 of South Dakota, have invented a new and Improved Saw-Frame, of which the following is a full, clear, and exact description.

This invention is an improvement in saw-frames, relating especially to that class of saw-frames for receiving a detachable blade.

The object of the invention is not only to generally improve the construction of saw-frames of this character, making them more convenient to handle, cheapening and simplifying them, but also to provide a novel and easily-operated means for stretching the saw-blade in the frame after it is applied thereto.

Reference is to be had to the accompanying drawings, forming a part of this specification, in which similar characters of reference indicate corresponding parts in all the figures.

Figure 1 is a side elevation of the saw complete with the handle thereof thrown to operative position to stretch the blade in the frame. Fig. 2 is a fragmentary view of an end of the saw-frame carrying the blade-tightening means with a handle or lever thereon thrown to inoperative position for releasing the blade or to admit of one being applied thereto. Fig. 3 is a detail view illustrating the construction of one member of the saw-frame. Fig. 4 is a transverse sectional view on the line 4 4 of Fig. 1, and Fig. 35 is a transverse horizontal section on the line 5 5 of Fig. 1.

The frame of the saw is preferably constructed of a single piece of pipe comprising 40 front and rear bars 1 and 2, connected by a horizontal bar 3, providing a frame of the U type. The ends of the bars 1 and 2 are flattened and the frame slotted to receive one end of a saw-blade 4, held between the flattened portions at the end of the bar 1 by a pin 5 or other equivalent means. The flattened portion of the saw-frame at the end of the bar 2 is cut out on one side, as shown in Fig. 5, to form a pocket for containing a 45 tightening-lever 6, said lever being flattened and provided with a handle 7, extending therefrom, of cylindrical or other convenient shape and operable not only to tighten the blade, but also serving as a handle for working the saw. The flattened portion forming 55 said pocket has passing through each side of

it two alining and rearwardly-inclined slots 8, through which a rivet 9 passes when the saw is assembled, embracing at each side links 10, the latter provided at their opposite 60 ends with inset portions 11, which are apertured in order to receive and connect them with the opposite end of the blade 4, as by a pin 12. The rivet 9 passes through the lever 6 near its outer edge at such a distance from 65 the end of the lever that when the latter is turned about the rivet as a center a cam-toe 13 will ride on the inner face of the pocket and force the rivet 9 to the opposite ends of the slots 8 and hold the lever in the down- 70 wardly-extending position shown in Fig. 1.

The pocket containing the lever 6 is extended at its front side at 14 in order to insure a better bearing-surface when the lever is in closed position. By means of this 75 tightening mechanism it is only necessary to throw the handle upward at an angle to the frame, as shown in Fig. 2, to remove or place a blade in the frame.

Although I have described the invention 80 in detail, it is evident that various immaterial changes may be made without departing from the spirit of my invention, and I consider that I am entitled to such modifications as fall within the scope of the annexed claims. 85

Having thus described my invention, I claim as new and desire to secure by Letters Patent—

1. A saw-frame having one end slotted for receiving one end of a blade, a pocket formed 90 at the opposite end of the frame having slots, a handle for the frame pivoted at one end in the slots of the pocket, a cam at the extremity of the pivoted end of the handle, and means for connecting the handle with the opposite end of the blade, whereby when it is turned downwardly the saw is tightened in 95 the frame.

2. A saw-frame comprising a pipe bent 100 into U shape with flattened ends, one of said ends being slotted to receive one end of a blade and the opposite end cut out at one side to form a pocket having a rearwardly-inclined slot at each side thereof, a lever having a cam end arranged in the pocket, links 105 for receiving the opposite end of the blade, and a rivet passing through the lever, slots and links pivotally connecting the latter at opposite sides of the pocket.

3. A saw-frame made from a single piece of 110 pipe with flattened ends, one of said ends being slotted for receiving a blade, the opposite

end being cut out at one side providing a pocket, a handle pivotally mounted in the pocket, and means operable by the handle for tightening the blade in the frame.

5 4. A saw-frame having arranged at its respective ends means for attaching one end of a blade and a slotted pocket, means for attaching the opposite end of the blade, comprising links pivotally connected at opposite
10 sides of the pocket through the slots therein,

and a lever in the pocket pivotally mounted on the pivot of the links and having a cam end for tightening the blade in the frame.

In testimony whereof I have signed my name to this specification in the presence of 15 two subscribing witnesses.

AUGUST ALLEN.
